VULCANIZING MACHINE

Thomas M. Knowland, Belmont, Mass., assignor
to Boston Woven Hose & Rubber Company,
Cambridge, Mass., a corporation of Massachu-
sets

Application August 12, 1937, Serial No. 158,723

6 Claims. (Cl. 18—6)

This invention relates to vulcanizing machines of the continuous vulcanizing type and employing a vulcanizing drum with which cooperates an endless tension band, the material to be vulcanized being continuously passed through the machine between and in pressure contact with the tension band and the arcuate surface of the drum. The drum is heated to vulcanizing temperature as is also the band, the latter being heated by heating jackets held in surface contact therewith. The invention herein relates primarily to the heating jackets and the primary object thereof is to provide such heating jackets superior to those heretofore known and used.

15 My improved jacket is preferably of segmental construction and each segment has an arcuate surface located adjacent to and cooperating with the tension band where it engages the drum. Each segment is furthermore mounted for movement toward and from the drum and preferably mounted to pivot on an axis extending along the drum and located intermediate the side edges of the jacket whereby the jacket may automatically seat into full surface contact with the band. In accordance with another feature of the invention, such contact is maintained resiliently by springs located rearwardly of each segment and normally urging the segments forwardly and holding their arcuate surfaces in the desired pressure contact with the band. Other features and further details of the invention are herein-after more specifically described.

These and other features of the invention will be best understood and appreciated from the following description of a preferred embodiment thereof, selected for purposes of illustration and shown in the accompany drawing in which—

Fig. 1 is a side elevation of a machine embodying my invention.

40 Fig. 2 is an enlarged fragmentary view taken on line 2—2 of Fig. 1 and showing one of the jacket segments in rear elevation.

Fig. 3 is an enlarged sectional view taken on line 3—3 of Fig. 2.

45 Fig. 4 is a cross sectional view taken on line 4—4 of Fig. 3.

The heavy metal frame of the machine comprises side members 10 of similar shape rigidly connected and supported on a concrete foundation. The frame is designed to support three rolls over which passes a relatively wide steel tension band 11 in a generally triangular path with a re-entrant loop extending about the periphery of a large vulcanizing drum or cylinder 12 supported by the frame within the general

outline of the path of the band. Two of the band-supporting rolls 14 are located adjacent to and forwardly of the vulcanizing drum, and a third roll 16 is located rearwardly of the drum, the tension band being supported on these rolls 5 and engaging the drum. The band is brought to and held in the desired tension by hydraulic pressure in pressure cylinders 18 acting against the bearings 19 for the roll 16. The drum is rotated slowly in the direction indicated by the 10 arrow and the strip to be vulcanized is fed into the bite formed between the band and the drum as the band leaves the lower roll 14.

The vulcanizing drum 12 is steam heated to vulcanizing temperature as fully explained in 15 Patent No. 2,039,271 granted April 28, 1936, on an application of J. M. Bierer. That portion of the band which cooperates with the drum is engaged and heated by a plurality of segments 20 providing a heating jacket. Each such segment comprises a front plate 22 having an arcuate front surface 24 for engaging the tension band 11 as illustrated in Fig. 4. Housed beneath a metal cover 26 and heat insulating material 28 at the rear of the plate 22 are steam pipes 25 30, the elements 22, 26 and 28 being secured together by tap bolts 32 and edge plates 34.

Each end of each segment 20 is flanged at 36 and a roller 38 is carried by each flange midway between the side edges 34 of the segment. Each 30 such roller is arranged to ride in a radial guideway 40 formed in a block 42 secured by bolts 44 to an arcuate flange 46 bolted to a side member 10 of the main frame at 48. The two arcuate flanges 46 are spaced outwardly from the drum, 35 are respectively mounted on the two side members 10 and are concentric with the drum. The several segments are located in relatively close relation whereby providing a segmental jacket extending substantially 270° around the drum 40 (Fig. 1) and each segment is mounted for radial movement in its guideways 40 toward and from the drum and for pivotal movement about the axis of its rollers 38.

It is desirable that the jacket segments shall 45 have their arcuate surfaces pressed uniformly into contact with the band and with a pressure maintaining a firm contact without causing undue friction therebetween. In accordance with my invention, I secure this contact through resilient means which, in conjunction with the mounting of the segments for radial and pivotal movement, provides such firm and uniform contact. The resilient means is preferably in the form of springs and these springs may be ar- 50 55

ranged to apply their pressure at any point or points on the segments, such as at the pivotal axis of the rollers 38 or at opposite sides thereof. In the drawing I have shown two springs 50 at each end of each segment and located respectively at opposite sides of a roller 38. These springs are hung by bolts 52 from the stationary flanges 46, each spring being supported on a bolt between the flange 46 and an angle plate 54 secured to the end of the segment. The springs act to force the segments radially toward the drum and into contact with the band thereon, and the extent of such movement may be limited by adjusting nuts on the bolts 52.

15 The strip material 56 to be vulcanized is fed into, through and from the machine in the direction indicated by the arrows in Fig. 1, and the band 11 is held under constant tension placing the strip under heavy pressure between the 20 opposing surfaces of the band and drum as vulcanizing thereof progresses. These surfaces are heated to vulcanizing temperature and it will be apparent from Figs. 1 and 4 that the segments are held in firm and uniform contact with the 25 band during the vulcanizing treatment whereby heating the band efficiently and uniformly. The curvature of the surfaces 24 of the segments correspond to the curvature of the band on the drum and the springs 50, particularly in cooperation 30 with the pivotal supporting means at 38, provide a pressure which remains constant, uniform and resilient without causing undue friction between the band and the surfaces 24. It will be apparent that the mounting of the jackets for radial 35 movement permits the vulcanizing of belts of varying thickness and the maintaining of the jackets in direct contact with the band 11 permits heating of the band by direct contact of the jackets therewith. Thus heating the band makes it possible to keep the band and drum 40 surfaces approximately at the same vulcanizing temperatures with maximum economy and results in producing a superior product uniformly vulcanized from both sides.

45 Having thus described my invention, what I claim as new and desire to secure by Letters Patent of the United States is:

1. A continuous vulcanizing machine, comprising a frame, a cylindrical vulcanizing drum thereon, an endless band having an open loop portion 50 passing around a substantial arcuate portion of the drum, a heating jacket having a concave 55 arcuate surface located adjacent to and adapted to have direct and continuous surface contact with said loop portion of the band, means for heating the jacket, means fixed to the frame and providing a radial guideway at each end of the jacket and intermediate the side edges thereof, means including rollers riding in said guideways 60 for supporting the jacket for pivotal movement about the axis of the rollers, and means for forcing the jacket radially inward to press said arcuate surface thereof into said surface contact with the loop portion of the band.

65 2. A continuous vulcanizing machine, comprising a frame, a cylindrical vulcanizing drum thereon, an endless band having an open loop portion 65 passing around a substantial arcuate portion of the drum, a segmental heating jacket extending along the drum and having concave arcuate surfaces located adjacent to and cooperating with said loop portion of the band, means for heating the jacket, two arcuate supporting

elements fixed to the frame respectively at the ends of the jacket, means including cooperating members carried by the elements and each segment for supporting each segment on said elements for radial movement toward and from the band and for pivotal movement about an axis extending along the drum, and resilient means between said elements and the segments and urging the segments toward the band and said arcuate surfaces thereof into direct and continuous surface contact with the loop portion of the band. 5 10

3. A continuous vulcanizing machine, comprising a frame, a cylindrical vulcanizing drum thereon, an endless band having an open loop portion 15 passing around a substantial arcuate portion of the drum, a heating jacket having a concave arcuate surface located adjacent to and cooperating with said loop portion of the band, means for heating the jacket, locating means fixed to the frame and providing a radial guideway at each end of the jacket and intermediate of the side edges thereof, guide members on the jacket riding in said guideways and permitting pivotal movement of the jacket about a common axis extending through said members at both ends of the jacket, and means for forcing the jacket inwardly to engage said arcuate surface thereof directly and continuously with the band. 20 25

4. The machine defined in claim 3 wherein the 30 jacket forcing means includes springs located at opposite sides of said axis.

5. A continuous vulcanizing machine comprising a frame, a cylindrical vulcanizing drum thereon, an endless band having an open loop portion 35 passing around a substantial arcuate portion of the drum, a segmental heating jacket extending along the drum and having concave arcuate surfaces located adjacent to and in position to cooperate with said loop portion of the band; flanges 40 fixed to the frame and spaced relatively to each other longitudinally of the drum and extending about the drum in spaced relation thereto, means supporting the segments on the flanges for movement bodily toward and into surface 45 contact with said loop portion of the band, said means supporting the segments with sufficient looseness to permit the concave surfaces to come into uniform surface contact with the band, means for heating the segments, and resilient means normally pressing the segments inwardly to contact their said surfaces with the loop portion of the band. 50

6. A continuous vulcanizing machine comprising a frame, a cylindrical vulcanizing drum thereon, an endless band having an open loop portion 55 passing around a substantial arcuate portion of the drum, a heating jacket having a concave arcuate surface located adjacent to and adapted to have direct and continuous surface contact with said loop portion of the band, means for heating the jacket, and means including guides fixed to the frame and pivot elements carried by the jacket and cooperating with the guides for locating the jacket on the frame for movement toward and from the drum and for pivotal movement about the pivot axis of said elements which axis extends parallel to the axis of the drum and is located intermediate of the side edges of the jacket and outwardly of said loop 60 portion of the band. 65 70

CERTIFICATE OF CORRECTION.

Patent No. 2,182,317.

December 5, 1939.

THOMAS M. KNOWLAND.

It is hereby certified that error appears in the printed specification of the above numbered patent requiring correction as follows: Page 2, second column, line 27, claim 3, for the word "jacket" first occurrence, read jacket and located outwardly of said loop portion of the band; and that the said Letters Patent should be read with this correction therein that the same may conform to the record of the case in the Patent Office.

Signed and sealed this 6th day of February, A. D. 1940.

Henry Van Arsdale,
(Seal) Acting Commissioner of Patents.
